[57] CLAIM

The ornamental design for an anti-theft steering-wheel restrictor, as shown and described.

DESCRIPTION

FIG. 1 is a front elevational view of an anti-theft steering-wheel restrictor showing my new design as would be attached to a vehicle steering wheel;

FIG. 2 is a top plan view thereof;

FIG. 3 is a bottom plan view thereof;

FIG. 4 is a front elevational view thereof;

FIG. 5 is a back elevational view thereof;

FIG. 6 is a right side elevational view thereof; and,
FIG. 7 is a left side elevational view thereof.

The wheel depicted by means of broken lines in FIG. 1, is shown for illustrative purposes only and forms no part of the claimed design.
